FASTENER FOR A CARTON DIVIDER

Hazen A. Gustafson, Beloit, Kans.

Application April 18, 1958, Serial No. 50,515

Term of patent 14 years

(Cl. D58—26)

Fig. 1

Fig. 2

Fig. 3

Fig. 4

Fig. 1 is a view in perspective of a fastener for a carton divider, showing my new design.

Fig. 2 is a bottom plan view thereof.

Fig. 3 is a side elevation thereof.

Fig. 4 is an end view thereof in elevation.

I claim:

The ornamental design for a fastener for a carton divider, as shown.
